UNITED STATES PATENT OFFICE.

BENJAMIN F. BEANE AND ROY P. BENNETT, OF NEW PARIS, OHIO.

FIRE-ALARM SYSTEM.

No. 821,581.

Specification of Letters Patent.

Patented May 22, 1906.

Application filed July 10, 1905. Serial No. 269,103.

To all whom it may concern:

Be it known that we, BENJAMIN F. BEANE and ROY P. BENNETT, citizens of the United States, residing at New Paris, in the county of Preble and State of Ohio, have invented certain new and useful Improvements in Fire-Alarm Systems; and we do declare the following to be a full, clear, and exact description of the invention, such as will enable others skilled in the art to which it appertains to make and use the same.

Our invention relates to improvements in fire-alarm systems for small towns and villages which have a volunteer fire department.

One object of the invention is to provide a signal system of this character which will sound a general alarm at a central station and independent alarms at the homes of the firemen or members of the volunteer department.

Another object of the invention is to provide a simple and efficient electrically-controlled means for mechanically operating an alarm-bell.

A further object of the invention is to improve and simplify the construction and operation of an apparatus of this character, and thereby render the same more certain, durable, and effective in use.

With the above and other objects in view the invention consists of certain novel features of construction, combination, and arrangement of parts, as will be hereinafter described and claimed.

In the accompanying drawings, Figure 1 is a side elevation of our improved alarm mechanism with the electrical connections illustrated diagrammatically, and Fig. 2 is an end elevation of the mechanism shown in Fig. 1.

Referring to the drawings by numeral, 1 denotes a bell or other alarm device which may be mounted in a suitable tower 2, constructed for that purpose, as illustrated in the drawings, or it may be mounted in the top of a building or at any other suitable place which is centrally located in a small town or village, so that the bell may be heard by all or a large number of the inhabitants. The support or tower 2 may be of any suitable construction, and the bell 1, which is suspended in its top, as shown, is sounded by a rotary clapper 3, which is in the form of a bar secured at its cen-

ter upon a shaft 4, having at its ends pivotally-mounted tappet heads or devices 5, which are adapted to strike the bell 1 as the shaft 4 is rotated. These tappet devices are preferably in the form of rings or washers, which are loosely mounted in the outer ends of the clapper-arms 3, so that they will be thrown outwardly by centrifugal force to strike the bell 1 as the shaft 4 rotates. Said shaft is mounted in bearings in a suitable frame 6, which is provided upon the upper portion of the tower 2, and upon one end of said shaft is a pinion 8, which meshes with a large gear 9, secured upon a second shaft 10, which is also mounted in bearings in the frame 6. The gear 9 is secured upon one end of the shaft 10 and at its opposite end is loosely mounted a sprocket-wheel 11. This sprocket-wheel 11 is free to rotate independent of the shaft 10, in one direction, but is caused to rotate therewith in the opposite direction by a spring-actuated pawl 12, which is pivoted upon it and which engages a ratchet-wheel 13, secured upon said shaft 10. The sprocket-wheel 11, which is disposed in the upper portion of the tower, is connected by a sprocket-chain 14 to a sprocket-wheel 15, which is suitably journaled in a frame 16, provided in the lower portion of the tower. Upon the sprocket-chain 14 is secured a weight 17, which when in its elevated position (shown in Fig. 2 of the drawings) and the sprocket-wheel 15 is released by a trip device 18, mounted in the lower portion of the tower, is adapted to descend to cause the sprocket-chain 14 to rotate the shaft 11, which in turn rotates the shaft 4 and the clapper 3 to sound the bell. A crank-handle 19 may be provided upon the shaft of the sprocket-wheel 15 or any other suitable means may be provided for rotating said wheel to elevate the weight 17 to the position shown in Fig. 2 of the drawings. It will be seen that owing to the pawl-and-ratchet connection 12 13 the shaft 10, and hence the shaft 4, will only be rotated as the weight 17 descends, the sprocket-wheel 11 turning independent of the shaft 10 when said weight is elevated.

The trip device 18, by means of which the alarm mechanism just described is set in operation, is adapted to be operated from any one of a number of substations which are lo-

cated at different points throughout the town. The trip 18, which is in the form of a lever, is controlled by an electromagnet 20, which in turn is actuated by the closing of an electric circuit, as illustrated diagrammatically in Fig. 1 of the drawings. The lever or trip 18 is pivoted intermediate its ends, as shown at 21, and has one of its ends engaged with the teeth of the sprocket-wheel 15, and its opposite end is adapted to be supported when the trip is in its locked position (shown in Fig. 1 of the drawings) by a hook 22 upon the armature 23 of the electromagnet 20, said armature being pivotally mounted in a hanger 24, provided upon the supporting-base of the magnet. The coils of the magnet 20 are included in a normally open electrical circuit 25, which also includes an electric battery or other generator 26, an annunciator 27, and a series of push-buttons of other circuit-closing devices 28, which are arranged at the different substations throughout the town. It will be understood that the device 28 may be of any form. Instead of employing push-buttons we may use thermostatically-closed circuit-closures, which may be located at various points, such as warehouses, store-rooms, elevators, flour-mills, and the like. These thermostatic circuit-closures, it will be understood, will close the circuit to sound the fire-alarm when the temperature at the place where it is located rises to a predetermined degree. It will be seen that when any one of the devices 28 is actuated to close the circuit 25 the annunciator 27 will be actuated to indicate from which substation the alarm is sounded, and the magnet 20 will be energized to attract its armature 23, and thereby release the trip-lever 18. When the latter is released, it frees the sprocket-wheel 15 and permits the weight 17 to descend, and thereby sound the alarm-bell 1.

In order to simultaneously sound individual alarm devices located at the homes of the members of the fire department of the town, we provide a separate normally open electric circuit 29. This circuit 29 includes the battery or generator 26, a series of electric bells or other translating devices 30, which are located in the rooms of the firemen, and the trip-lever 18, which latter when it swings to its released position is adapted to engage an electrical contact-point 31, and thereby close the said open circuit 29, so that the bells or signaling devices 30 will be actuated simultaneously with the bell 1. If desired, we may also include in the circuit 29 an electric lamp 32, which is disposed adjacent to the annunciator 27 to permit the latter to be more readily seen.

From the foregoing description, taken in connection with the accompanying drawings, the construction and operation of the inven-

tion will be readily understood without requiring a more extended explanation. 65

While we have shown and described the preferred embodiment of our invention, it will be understood that we do not wish to be limited to the precise showing herein set forth. Instead of the weight 17 for actuating 70 the shaft 10 we may substitute a spring, and various other changes in the form, proportion, and the minor details of construction may be resorted to without departing from the principle or sacrificing any of the advantages of 75 this invention.

Having thus described our invention, what we claim as new, and desire to secure by Letters Patent, is—

1. In a fire-alarm system, the combination 80 of a bell, a rotary clapper for said bell, a winding mechanism, a trip for holding said mechanism in inoperative condition, an electromagnet, an armature for actuating said trip for releasing the winding mechanism, an 85 electric generator, an annunciator, circuit-closing devices, and an electric circuit including said generator, said annunciator, and said circuit-closing devices, substantially as described. 90

2. In a fire-alarm system, the combination of a sounding device, means for operating the sounding device, comprising a winding mechanism, an electromagnet, a trip actuated by the armature of said electromagnet for releasing said winding mechanism, an electric generator, a series of electric bells or other translating devices arranged at different points, and an electric circuit including said generator, said electric bells or translating 100 devices, and said trip, substantially as described. 95

3. The combination of a suitable support, a bell mounted therein, a shaft, a rotary clapper upon the latter, a second shaft, gearing 105 connecting said shafts, a rotary element, mounted upon said second shaft to turn therewith in one direction and independent thereof in the reverse direction, a second rotary element, an endless flexible connection 110 passed about said elements, a weight carried by said flexible connection, a trip device for holding said second rotary element against movement, an electromagnet for controlling said trip-lever, and means for actuating said 115 electromagnet from different points, substantially as described. 110

4. The combination of a suitable support or tower, a bell mounted therein, a shaft disposed beneath said bell, a rotary clapper 120 upon said shaft for sounding said bell, a second shaft, gearing between said shafts, a sprocket-wheel loosely mounted upon said second shaft, a pawl-and-ratchet connection between the latter and said sprocket-wheel, a 125 second sprocket-wheel mounted in the lower

portion of said tower, a sprocket-chain connecting said sprocket-wheel, a weight upon said sprocket-chain, a trip-lever for holding said second sprocket-wheel against rotation, and electrically-operated means for controlling said trip-lever, substantially as described.

5 In testimony whereof we have hereunto set

our hands in presence of two subscribing witnesses.
